UNITED STATES PATENT OFFICE

154,729

DESIGN FOR A GOBLET OR SIMILAR
STEM GLASSWARE

Louie Wohinc, Weston, W. Va..

Application August 6, 1946, Serial No. 132,302

Term of patent 3½ years

(Cl. D36—8)

To all whom it may concern:

Be it known that I, Louie Wohinc, a citizen of the United States, residing at Weston, in the county of Lewis and State of West Virginia, have invented a new, original, and ornamental Design for Goblet or Similar Stem Glassware, of which the following is a specification, reference being had to the accompanying drawing, forming part thereof, in which—

Fig. 1 is an elevational view of a goblet or similar stem glassware, showing my new design;

Fig. 2 is a top plan view thereof; and

Fig. 3 is a perspective view of the same.

The dominant features of the design reside in the specific form and shape of the bowl portion thereof, best shown in Fig. 1 of the drawing.

I claim:

The ornamental design for a goblet or similar stem glassware, substantially as shown and described.

LOUIE WOHINC.
